UNITED STATES PATENT OFFICE.

THOMAS CLARENCE OLER, OF IOWA FALLS, IOWA.

MILKING-STOOL.

1,138,781.

Specification of Letters Patent. Patented May 11, 1915.

Application filed November 6, 1914. Serial No. 870,543.

To all whom it may concern:

Be it known that I, THOMAS C. OLER, a citizen of the United States of America, and resident of Iowa Falls, Hardin county, 5 Iowa, have invented a new and useful Milk-
ing-Stool, of which the following is a specification.

The object of this invention is to provide an improved construction for milking-
10 stools adapted to support the milker and also a pail to receive the milk.

My invention consists in the construction, arrangement and combination of elements hereinafter set forth, pointed out in 15 my claims and illustrated by the accompanying drawing, in which—

Figure 1 is a plan, Fig. 2 a side elevation and Fig. 3 a rear elevation of my device.

In the construction of the device as shown 20 the numeral 10 designates a frame made of a single bar of metal and having parallel contiguous arms and a loop 10^a connecting said arms, said loop being adapted to receive and support a pail. Legs 11, 12, each 25 made of a single bar of metal, are arranged parallel with each other and on opposite sides of and at right angles to the arms of the frame 10 and are secured adjustably to said arms by bolts 13, 14 passing through 30 registering holes 15 in the arms and through the legs. Several holes 15 are provided in the arms in order that the legs may be adjusted longitudinally of said arms. The 35 upper ends of the legs 11, 12 are turned outwardly and a seat 16, of any suitable ma-

terial, is mounted on and secured to said outturned portions of the legs. The legs preferably cross the plane of the frame 10 in order that (when in use) the seat 16 may occupy a higher horizontal plane than the 40 loop 10^a containing the pail. Legs 17, 18 are fixed to opposite sides of the loop 10^a and are on opposite sides of the median line of the frame 10. The spaced legs 17, 18 coöperate with the legs 11, 12 in maintaining the stability of the device. 45

I claim as my invention—

1. A milking stool comprising a frame made of a single metal bar doubled on itself and bent on an arc at its center to form a 50 pail-holding loop, legs on said loop, legs secured to and adjustable longitudinally of said frame and spaced from said loop, and a seat on the latter legs.

2. A milking stool comprising a frame 55 made of a single metal bar bent on an arc at its center to form a pail-holding loop, supporting legs on opposite sides of and fixed to said loop, supporting legs crossing said frame at the end thereof opposite to 60 said loop, means for securing the latter legs to and adjustable longitudinally of said frame, and a seat fixed to the latter legs above said frame.

Signed by me at Iowa Falls, Iowa, this 65
28th day of October, 1914.

THOMAS CLARENCE OLER.
